SPRING MECHANISM FOR OIL WELL
DEVICES

Helmut Hügel, Campina, Rumania, assignor to
Shell Development Company, San Francisco,
Calif., a corporation of Delaware

Application June 8, 1939, Serial No. 278,011

2 Claims. (Cl. 185—37)

This invention relates to spring-impelled clockwork mechanisms and pertains more particularly to a clockwork driving mechanism for oil well devices, such as pressure or temperature recorders.

It is known in the art to employ spiral leaf springs under tension to move a stylus with regard to a strip of paper in contact therewith in order to obtain a chart recording a variable, such as pressure or temperature, with respect to the time element. Due, however, to the limited maximum diameter of the devices capable of being lowered into oil wells, it is difficult to store in a clockwork spring mechanism an amount of energy sufficient for satisfactory operation. These mechanisms, therefore, either fail to exert the necessary force to overcome the friction encountered in moving the desired parts with regard to each other while making a record, or succeed in exerting such force only for relatively short periods of time so that the useful operation time of the device is unduly restricted.

Thus, a strong spring mechanism, while capable of exerting a sufficient force for effectively actuating all the necessary working parts of a recording mechanism to produce the desired record, usually dissipates its energy too quickly to permit a complete survey of the conditions prevailing in a well to be effected in one run, since a total of only about three or four revolutions of the recording spindle or shaft can be obtained with such a spring. On the other hand, a weak spring mechanism, capable of giving six or more revolutions of the recording spindle, fails to exert the force necessary to overcome the friction of the working parts and to effectively actuate said parts in such a manner as to produce the desired record.

It is, therefore, an object of this invention to provide an actuating mechanism for oil well recording devices comprising a plurality of spiral leaf springs axially arranged in series in such a manner as to be lodged in a housing of relatively small diameter.

It is another object of this invention to provide an actuating mechanism for oil well recording devices comprising a plurality of relatively strong spiral leaf springs coupled with each other in series, whereby the force exerted by said spring coupling arrangement is sufficient to actuate the recording device throughout the whole period of operation of said device, while said period of operation of the device is substantially equal to the sum of the periods of operation of the individual springs forming said coupling.

It is another object of this invention to provide an actuating mechanism for oil well recording devices especially suitable for use in connection with the pressure and temperature recorders described in my co-pending applications Serial No. 184,780, filed January 13, 1938, and Serial No. 247,749, filed December 27, 1938, respectively.

Further objects and advantages of the invention will be apparent from the following description taken in connection with the accompanying drawings, wherein:

Figure 1 is a schematic longitudinal cross-sectional view of the upper portion of a preferred embodiment of a pressure recorder of my above-mentioned co-pending application Serial No. 184,780.

Figure 2 is a longitudinal cross-sectional view of the lower portion of the same embodiment, particularly showing the present actuating mechanism.

Figure 3 is a longitudinal cross-sectional view of the first or any intermediate spring case or housing, with the leaf spring and a portion of its ball races removed.

Figure 4 is a transverse cross-sectional view taken along the line IV—IV of Figure 3.

Figure 5 is a longitudinal cross-sectional view of the last or lowermost spring case and case lock container, with its leaf spring, a portion of the ball races, studs and helical springs removed.

Figure 6 is a transverse cross-sectional view taken along the line VI—VI of Figure 5 with the studs and helical springs shown in place.

Figure 7 is an end view of the lock ring.

Figure 8 is a longitudinal cross-sectional view taken along the line VIII—VIII of Figure 7.

Figure 9 is an end view of the ratchet wheel holder.

Figure 10 is a longitudinal cross-sectional view taken along the line X—X of Figure 9, showing also the ratchet wheel as inserted into the holder.

Figure 11 is a transverse cross-sectional view taken along the line XI—XI of Figure 2.

Referring first to Figures 1 and 2 of the drawings, parts 1—11 inclusive represent schematically a pressure recorder of my above-mentioned application. Briefly, chart 1 records thereon the compound movement of a stylus 2, which is attached to shaft 3 of pressure-responsive piston 4. The fluid pressure within the well is impressed on the piston 4 from outside the device through ports 5 and is transmitted by means of diaphragm 6 to liquid filling the chamber 7, tube 8, and chamber 9, containing also piston 4, which moves axially against the spring 10 in response to pre-

- sure changes of the fluid. The time element is recorded on the chart 1 and static friction of the pressure-responsive piston 4 is minimized by means of the rotational motion imparted by the actuating spring mechanism of the present invention to the recorder stylus 2 and spindle 11 through spring 10, piston 4 and shaft 3, as explained in my above-mentioned application Serial No. 184,780.
- 10 The recorder spindle 11 is supported at its lower end by ball race 12 and is attached to the upper end of a clock axis or shaft 13 of the present spring mechanism by means of a coupling 14 or any other suitable means. About the clock axis 13, which runs axially within the tubular housing 15, are fitted spring cases or housings 16, 17 and 18 containing spiral leaf springs 19, 20 and 21, said cases being rotatably aligned with each other by means of ball bearings 22-27 inclusive. The spring mechanism is protected from contamination by the well fluid by means of an end case plug 28 which fits slidably about the clock axis or shaft 13 and within the housing 15.
- 15 Referring to the more detailed illustrations in Figures 3, 4, and 5, the upper spring case 16 (similar to spring case 17), shown with the spring, and a portion of the ball races removed, consists of a tubular member having a portion 16 of enlarged diameter, and a portion 16a of reduced diameter. The tubular portion 16 is turned to an outside diameter suitable for slidably fitting within casing 15, and has an inside bore suitable for forming a housing for ball bearings 22 and 23, by means of which the spring case is rotatably mounted on the clock axis 13, and for spring 19 (not shown in Figure 3) mounted in the space defined by the case 16, the clock axis 13, and ball bearings 22 and 23. The tubular portion 16a is turned to an outside diameter 20 permitting it to be inserted within the next spring case 17 and within the leaf spring 20 contained in said case 17. The tubular portion 16a has also an internal bore 16b adapted to fit slidably around clock axis 13. The outer end of spiral leaf spring 19 is attached to the case 16 by means of a spring holding nut 29, shown in Figures 3 and 4, while its inner end is held to the clock axis 13 by means of a barb 30 on said axis. The spring 20 within case 17 (as well as all other springs except the above-mentioned uppermost spring 19) is held in the same manner, except that its inner end is not affixed to a barb on the clock axis, but to a barb 30 on the member 16a of the preceding case projecting into case 17. In this manner, 25 it will be seen that the spring cases are adapted for rotational motion with regard to each other, to the casing 15, and to the clock axis 13.
- 30 The lowermost spring case 18 (shown in detail in Figures 5 and 6) consists of an upper portion 21 and similar to the portion 16 of the first and following spring cases, and of a lower portion 32 of solid cross-section, but provided with a bore 33b fitting slidably around a tube 34a which in turn fits slidably around the clock axis 13; said lower portion 32 is also provided with slots 33a radiating from said bore 33b. This portion of the lowermost spring case serves as a case lock container, the radial slots 33a carrying studs 34 which are forced outwards by means of small helical springs 35 to engage grooves 36 provided in the walls of casing 15, whereby the spring case 18 is prevented from rotation with regard 35 to said casing. The helical springs 35 rest

against the tube 34a, surrounding the clock axis 13.

Within the lowermost spring case 18 is a lock ring 37 (shown in Figures 7 and 8) having a central bore fitting slidably around the clock axis 13 and fastened to the upper face of the solid body of the case lock container by means of screws in holes 37a. This lock ring prevents any upward axial displacement of the studs 34 and the tube 34a. The downward axial displacement of the studs 34 is prevented by a ratchet wheel holder 38 (shown in Figures 9 and 10), attached to the lower face of the solid body of the case lock container by means of screws in holes 38a. This holder is generally similar to the lock ring 37, but is provided with a square axial opening 38b adapted to receive a square cross-section projection 39a of a ratchet wheel 39 which is mounted on the clock axis 13 (as shown in Figure 10). Cross-sections along the lines X-X and Y-Y in Figures 7 and 9, respectively, correspond to the view of these parts shown in Figure 2.

Rotatably mounted within the casing 15 below the ratchet wheel 39 is a clockwork movement 40, comprising upper and lower plugs 41 and 42, a concentric tubular holder 48, serving as a protective tube or housing for said clockwork movement, and movement plates 46. The upper and lower plugs 41 and 42, consist of cylindrical members, having two parallel longitudinal portions 30 cut away from each plug to form a narrowed portion 47 with parallel faces. The narrowed portions 47 of the plugs face each other and fastened to the parallel faces thereof are the movement plates 46, which are thereby carried between the plugs 41 and 42. The remaining cylindrical portion 41a of the plugs has the tubular holder 48 attached thereto. As shown in Figure 11, attached to the upper face of plug 41 is a pawl 43 pivoted by means of a pawl pin 44 and held against the ratchet wheel 39 by means of a pawl spring 45 likewise attached to the upper plug 41. The pawl engages the ratchet wheel in such manner that the clockwork movement 40 is permitted to rotate with regard to the last or stationary leaf spring case only in one direction, that is, the direction in which springs 19, 20 and 21 spiral inward. The upper plug 41 has an axial bore which permits slidable passage therethrough of the clock axis or shaft 13.

The clockwork movement 40 further comprises a series of gears and wheels pivotably mounted between the movement plates 46 and operatively connected to a main spring arbor gear 49 on the lower end of the clock axis 13 by means of a main mitre gear 50. Reducing gears 51 permit the main mitre gear 50 to actuate the timing or escapement mechanism which comprises an escape wheel 52, a pallet fork 53, a balance wheel 54, and a hair spring 55.

A threaded bore into the lower transverse face of the lower movement case 42 permits the attachment of a winding spindle 56 which extends downward, carries bumpers 57 of resilient material, such as rubber, and terminates in a winding nut 58. A tubular member 59 is threadably connected to the housing 15 and forms a housing for the bumpers 57 and is provided with an internal shoulder or portion of narrowed bore, which serves as a stop for the bumpers 57 which in turn support the clockwork movement. A bottom plug 60 is threadably attached to the lower end of the tubular member 59.

To wind the clock mechanism, which is assembled as described above, the bottom plug 60

is removed and by means of a key, winding nut 58 is revolved, which turns the winding spindle 56, clockwork movement 40, clockwork axis 13, and spring cases 16, 17 and 18, whereby the spiral leaf 5 springs 19, 20 and 21 are tensed in the order named. Then the bottom plug 60 is replaced and the recorder with the improved spring mechanism of the present invention is ready to be lowered into the borehole by means of a wire line or other suitable means. Release of the energy thus stored in the springs during operation causes a rotation of the clock axis or shaft 13 through the timing mechanism of the clockwork movement as the stationary ratchet 39 and pawl 42 rigidly engage 10 the clockwork movement holder with the last or stationary spring case or holder and prevent release of the tension by turning of the clockwork movement 40 and winding spindle 56 in a direction opposite to the winding direction.

20 Although the spring mechanism hereinabove illustrated and described contains, for purposes of simplicity, only three spiral leaf springs, it is to be understood that a greater or lesser number of such springs may be used while maintaining 25 the principle of a plurality of springs coupled in series, two being obviously the minimum number of springs capable of useful application with the arrangement described above. In practice a device of the present invention containing six spiral 30 leaf springs coupled in series has been found to be a preferred form for obtaining complete recordings throughout the length of deep wells. Normally with this arrangement the clockwork mechanism is so geared that the clock axis completes one revolution in about thirty minutes and with springs of suitable strength, the mechanism can make about twenty to twenty-five revolutions in a running time of about twelve hours and is able to pull a load of about 3 kg. on the circumference of a drum of 25 m. m. diameter fastened to the clock axis, when fully wound up, and over 2 kg. just before being completely unwound. This force has been found to be about two to three times greater than the maximum required to 40 turn the spindle of the pressure recording element referred to above. In another variation of this preferred form, with the reducing gears 51 in the clockwork movement having a ratio of about 1,500, the total running time was about two and 45 one-half to three days.

50 Although the embodiment herein disclosed is shown as applied to a well pressure recorder of my above-mentioned co-pending application, it is intended that the present spring mechanism may be coupled to other well pressure and temperature recorders and the like which require rotary motion for operation, since it is understood that the applicant is not limited to the particular type of construction shown in the drawings but may use 55 any other embodiment to carry his invention into

practice while applying the principle of the present invention.

I claim as my invention:

1. In a recording device adapted for operation in boreholes and comprising a cylindrical casing and a rotatable axial shaft within said casing, an actuating mechanism for said shaft, said mechanism comprising a plurality of spiral leaf springs mounted axially in series around the shaft, cylindrical housings for said springs having enlarged 10 hollow portions slidably fitting within the casing and surrounding said springs, each of said housings excepting the last having a reduced portion slidably fitting around the shaft and projecting within the enlarged portion of the next 15 housing, means attaching the outer end of the first spring to the enlarged portion of its housing and its inner end to the shaft, means attaching the outer end of each succeeding spring to the enlarged portion of its housing, and its inner end 20 to the reduced portion of the preceding housing, means fixedly attaching the last housing to the casing, each of said housings except the last being rotatable with regard to the casing, to the shaft, and to the other housings, and means for 25 tensing the springs by rotating the shaft.

2. In a recording device adapted for operation in boreholes, a fluid tight casing containing recording members comprising a chart and a marker in contact with each other, one of said members being fixedly attached to the casing, and the other member being attached to an axial shaft rotatable within said casing, an actuating mechanism for said shaft, said mechanism comprising a plurality of spiral leaf springs mounted axially 30 in series around said shaft, cylindrical housings for said springs having enlarged hollow portions slidably fitting within the casing, each of said housings excepting the last having a reduced portion slidably fitting around the shaft and projecting within the enlarged portion of the next 35 housing, whereby each spring is held in a space defined by the inner cylindrical wall of the enlarged portion of its housing and by the outer cylindrical wall of the reduced portion of the preceding housing, means attaching the outer 40 end of the first spring to its housing and the inner end to the shaft, means attaching the outer end of each succeeding spring to its housing and the inner end to the reduced portion of the preceding housing, means fixedly attaching the last housing to the casing, anti-friction bearings between the housings permitting their free rotation with regard to each other, means for tensing the springs by rotating the shaft, and a clockwork escapement mechanism in meshing engagement with the shaft whereby said shaft is caused to rotate at a uniform rate in the other direction 45 when the tension on the springs is released.

HELMUT HÜGEL. 60
